ERNEST C. HAZEL AND ERNEST C. HAZEL, JR., OF ATCHISON, KANSAS

COVER FOR PERMANENTLY BOUND BOOKS

Application filed December 16, 1931. Serial No. 581,286.

Our invention relates to book covers and more particularly to covers for permanently bound books of the type used for recording deeds, mortgages, general indexes to lands, court records and the like, and has for its principal objects to reduce the cost of manufacture and prolong the life of such books by forming the cover elements in separate pieces and hinging the side cover members to the back members in a manner to facilitate assembly and render the cover capable of withstanding the hard usage to which such books are submitted.

Books of the character above named are usually made up of sheets bearing printed forms and vary in thickness because of variation in thickness of the sheets and of the ink on the sheets, so that each book must have its cover fitted to it.

It is an object of our invention to facilitate fitting of the covers by compensating for such variation in construction of back members individual to the books.

Covers for such books are usually faced with leather cut from hides with both sides and the back cover portions in a single piece, resulting in considerable waste due to limitation of the number of such pieces that may be cut from a single hide.

It is a further object of our invention to reduce the cost of manufacture of such books without affecting their quality or appearance by saving in cost of leather resulting from more advantageous cutting of the hides in smaller pieces.

In accomplishing these and other objects of the invention, we have provided improved details of structure, the preferred forms of which are illustrated in the accompanying drawings, wherein:

Fig. 1 is a perspective view of a permanently bound book equipped with a cover constructed in accordance with our invention.

Fig. 2 is a similar view of the book showing the back member removed from the side members, hereafter referred to merely as covers to distinguish these from the connecting back members, and parts of one of the side covers broken away to better illus-

trate its connection with the body of the book, whereby the side covers are permanently incorporated as a part thereof.

Fig. 3 is a vertical cross sectional view through the book in open position.

Fig. 4 is an enlarged fragmentary perspective view of one end of the back member illustrating the mounting of the hinge sections thereon.

Fig. 5 is a detail perspective view of one of the hinge sections illustrated in Fig. 4.

Fig. 6 is an enlarged perspective view of one end of the back member illustrating the hub construction thereof and the method of covering the rivets employed for attaching the hinge sections.

Referring more in detail to the drawings:

1 designates a permanently bound book consisting of leaves or signatures 2 having their back edges 3 sewed, as at 4, and glued together to provide a rounded back face 5, as in standard book construction.

Secured to the rounded face 3, by gluing or the like, is a plurality of straps 6 having projecting ends 7 and 8 to which the side covers 9 and 10 are secured at the time the covers are assembled, whereby the covers may be incorporated in and become a permanent part of the book, as now described.

The side covers 9 and 10 may each comprise a plurality of superimposed layers of cloth board or the like, for example three in number, as designated 11, 12 and 13, each of the layers being preferably formed of relatively stiff material such as cloth board cut to conform to the shape of the book. The upper and lower edges 14 and 15 and the front edge 16 of the cover layers preferably extend beyond the boundaries of the leaves 2 with their rear edges terminating short of the rounded back face of the book to provide space for accommodating the nave portions of hinge sections 17 and 18 now to be described.

The hinge sections which are preferably pressed from suitable sheet metal each includes a flat, plate-like attaching portion 19 of substantially the length of the side covers and having along one edge a plurality of

naves 20 spaced apart to form socket portions 21 to accommodate naves on complementary hinge sections later described, the naves being formed by rolling back the edge 5 of the plate portion, as shown in Fig. 2.

In assembling the side covers the layers 11 and 12 are glued together after which the plate portions of the hinge sections 17 and 18 together with the ends of every other 10 one of the straps 6, are glued between the layers 12 and 13 as best illustrated in Figs. 2 and 3 with the plate portions of the hinge sections lying flat against layer 12, and the ends of the remaining straps are glued to 15 the opposite or inner face of the layer 13 (see Fig. 2). The outer face of layer 11 is then covered with suitable binding 22, such as leather, fabric, or the like. The free end of the cover material is tooled between layer 20 12 and the plate portion of the hinge sections 17 and 18 extending the full length of the cover. To allow easy turning and tooling of the cover material between layer 12 and the plate portion of hinge sections the 25 inner face of layer 12 along this edge is slightly beveled. The free edges of the binding are then drawn over the edges of the layers and glued to the inner face of layer 13. The remaining ends of the straps 30 are then drawn over the upper inner face of the layer 13 and glued thereto. Thus it is apparent that the ends of alternate straps 35 are glued to opposite faces of the layer 13. This is important because the space thus formed between the center and end parts 40 of the straps provides direct contact of the plate portion of the hinge with the layer 13 at points between the straps on that side of said layer, so that the attaching portion 45 of the hinge is glued to both the layers 12 and 13 and firmly imbedded therebetween.

A suitable inner cover 23 may be applied over the inner face of the layer 13 to cover the turned back edges of the binding as 45 well as the ends of the straps 6, to provide a finished appearance for the inner face of the covers.

The attaching portions of the hinge members are pressed into the adjacent layers 12 50 and 13 for securely anchoring the hinge members in position. The side covers 9 and 10, including the metal hinge sections, thus become a permanent part of the book since they are secured to the body portion thereof 55 by the straps 6. The rounded face 5 may then be covered, if desired, by paper, cloth or like strip 25 to hide the exposed portions of the straps 6.

26 designates the back member for completing the cover of the book, and preferably includes a molded body portion 27 of 60 suitable fiber or like material having substantially the same length as the side covers and of a width substantially corresponding 65 to the thickness of the book. The body of

the back member is also curved to conform to the curvature of the face 3 previously described.

Fixed to the inner curved face 28 of the body 27 are spaced hinge sections 29 and 30 cooperating with the hinge sections on the side covers to retain the back member to the book, as later described. The hinge sections 29 and 30 are also stamped from sheet metal and include longitudinal attaching 70 portions 31 having inwardly extending spaced tongues 32 adapted to extend over attaching areas of the hinge members and at the same time form spaces 33 therebetween through which portions of a covering 75 strip 34 may directly contact the body portion 27. The opposite edges of the attaching portions are rolled back upon themselves to provide naves 35 adapted to engage in the sockets 21 formed between the naves on 80 the complementary hinge sections 17 and 18, and are provided with similar sockets 36 to 85 likewise accommodate the naves 20.

The ends of the hinge sections 29 and 30 are provided with spurs 37 stamped from the 90 metal to form openings 38 through which rivets or the like 39 are inserted and projected through the body portion of the back to secure the hinge sections thereto. The spurs 37 are preferably extended towards 95 the ends of the strip at a slight incline to prevent longitudinal shifting of the hinge sections relative to the back member when the back member is being fitted to the complementary hinge sections on the side covers 100 and to retain them in position while the rivets are being applied.

The central portions of the hinge sections 29 and 30 are provided with similar spurs 40 inclined toward the naves 35 to prevent side- 105 wise movement of the hinge sections while they are being fitted to the hinge sections on the cover members. A rivet is also inserted through the openings 41 which are provided in the metal incidental to the 110 formation of the spurs 40. The rivets may be of the split type and the split ends 42 and 43 bent back over the curved outer face of the back member to be covered by the hubs 44 which may be built up of a plurality of 115 layers of fiber board shaped to give the effect desired.

In assembling the side and back cover members, the hinge sections are aligned and the back member pressed against the spurs 120 to anchor the spurs in the back member. Thus correct spacing of the hinge sections is automatically provided to assure their attachment at the proper points. The rivets are then applied to make a permanent connection.

To the outer curved face of the back member is glued a covering 45 which may be of the same material as the covering for the side members. The edges of the covering 130

are slotted to provide elongated tabs 46 that align with the socket portions 36 in the hinge sections and which are folded over and glued against the inner face of the back member to give added strength and prevent the hinge sections from pulling away from the back. The intermediate tabs 47 are shortened and tooled between the naves 35 and the inner face of the back member, as best illustrated in Fig. 4. Glued to the ends of the back member are sections of cord 48 over which extensions 49 on the ends of the cover may be folded to form heads 50 to complete the ends of the back member.

15 The inner curved face of the back member may then be covered by the inner covering strip 34 previously mentioned.

The back member is then ready to be attached to the side covers by rods 51 and 52 that are projected through the naves in the respective hinge sections to complete the assembly.

From the above it is apparent that the back member may be readily fitted to and assembled with the side covers to form a book having all the advantages of a permanently bound book of one-piece cover construction without the disadvantages of separation of the back member from the cover members commonly resulting from wear of a one-piece cover along the hinge lines, thus substantially increasing the length of wear and service of the book.

What we claim and desire to secure by Letters Patent is:

1. In a book cover of the character described including side and back cover members, hinge sections permanently attached to the respective cover members, spaced, parallel continuous hinge sections fixed to the back member, means on the back cover hinge sections for initially securing said hinge sections to the back member to adjust said hinge sections on the back member, fastening devices for permanently securing said back member hinge sections to the back member, and means pivotally connecting the hinge sections on the back member with the hinge sections on the side cover member.

50 2. A book cover of the character described including side cover members, hinge sections on the side cover members having spaced naves, a removable back cover member comprising a body member, separate continuous hinge sections fixed to opposite side edges of the body member and having naves aligning with the naves on the side member hinge sections, and rods extending through the naves of the respective cover member hinge sections for pivotally connecting the back member with the side members.

3. In a book cover of the character described including side cover members, hinge sections permanently mounted on the side

cover members, a back cover member, hinge strips extending along the edges of the back member having oppositely directed attaching and nave portions, fastening devices extending through said attaching portions into the back member to secure its hinge sections to the back member, hubs on the back member covering said fastening devices, a covering for the back member glued to and extending over the attaching portions of the back member hinge sections to supplement said fastening devices, and means pivotally connecting the hinge sections on the back and side cover members.

4. In a book cover of the character described including side cover members, hinge sections permanently mounted on the side cover members, a removable back cover member, hinge sections extending along the edges of the back member and having attaching portions spaced to locate the hinge sections in cooperative relation with the hinge sections on the side members, fastening devices extending through said attaching portions into the back member, a covering for the back member glued to and extending over the attaching portions of said last named hinge sections and glued to the back member between said spaced attaching portions, and means pivotally connecting the hinge sections on the back and side cover members.

5. In a book cover of the character described including side cover members, hinge sections permanently mounted on the side members each having a plurality of spaced naves, a back cover member, hinge strips extending along the edges of the back member having naves alternating with the naves on the side cover hinge sections, spaced anchoring tongues on the strip portions, fastening devices extending through said attaching portions and the back member, a fastening strip glued to the back member and extending over said tongues to supplement said fastening devices in securing said strip portions, and rods extending through the naves of the respective hinge sections to hingedly connect the back and side cover members.

6. In a book cover of the character described including side cover members, hinge sections permanently mounted on the side members having a plurality of spaced naves, a back cover member, hinge strips extending along the edges of the back member and having naves interfitting with the naves on the side cover hinge sections, spaced anchoring tongues extending from said hinge strips, a fastening strip glued to the back member and extending over and glued to said tongues to anchor the tongues to the back member, and rods extending through the naves of said hinge sections to hingedly connect the back and side cover members.

7. In a book cover of the character described including side cover members, hinge sections permanently mounted on the side cover members, a back cover member, hinge sections extending along the edges of the back cover member having attaching portions spaced to locate the side and back cover hinge sections in cooperative relation, fastening devices extending through said attaching portions and the back member, hubs on the back member covering said fastening devices, and a covering for the inner face of the back member extending over and secured to the attaching portions of said hinge sections.

8. In a book cover of the character described including side cover members, hinge sections permanently mounted on said side members having a plurality of spaced naves, a back cover member, hinge strips extending along the edges of the back member and having naves interfitting with the naves on the side cover hinge sections, fastening devices extending through said attaching portions and the back member, a covering extending over the outer face of said back member and having tabs extending between the naves on the hinge sections of the back member and glued over said strips, a cover strip member glued to the inner face of the back member and extending over said tabs, and rods extending through the naves of said hinge sections to connect the back cover member with the side cover members.

9. A book cover of the character described including side cover members, hinge sections permanently mounted on the side members, a back cover member, hinge sections having attaching strip portions extending along the edges of the back member, spurs arranged on the strip portions for retaining the strip portions in spaced relation when the back cover member is fitted to the side cover members to locate the hinge sections in position to mesh with the hinge sections on the side cover members, permanent fastening devices extending through said attaching portions and the back member, and means for pivotally connecting the hinge sections on the side cover members with the hinge sections on the back member.

10. In a book including permanently bound signature sections, side covers for the signature sections each comprising a plurality of layers of fiber board, flexible straps fixed to the signature sections having their ends secured between said layers, hinge sections having attaching portions located between said layers and fixed to the ends of said straps, means anchoring said attaching portions between said layers, a removable back for the side covers, and hinge sections on the back hingedly connected with the hinge sections on the side covers.

11. In a book including permanently

bound signature sections, flexible straps fixed to the signature sections, side covers for the signature sections permanently secured to said straps, hinge sections having attaching portions secured to said side covers and said straps, a removable back for the side covers, and hinge sections on the back pivotally connected with the hinge sections on the side covers.

12. In a book including permanently bound signature sections, side covers for the signature sections each comprising a plurality of layers of fiber board, flexible straps fixed to the signature sections and having free ends arranged so that the ends of every other strap engage one side of one of said layers and the ends of the intermediate straps engage the opposite sides of said layer, hinge sections having attaching portions located between said layers and engaging the ends of said straps and said layer at points between said straps, means anchoring said attaching portions between said layers, a removable back for said covers, and hinge sections on the back hingedly connected with the hinge sections on the side covers.

13. In a book cover of the character described including side cover members, hinge sections permanently mounted on the side members, a back cover member, hinge strips extending along the edges of the back member and engaging the hinge sections on the side cover members, spaced anchoring tongues on said hinge strips, an outer covering for the back member having tabs extending over said hinge strips between said tongues and sealingly engaged with the back member, an inner covering member for the back member covering said tongues and tabs and sealingly engaged therewith and with the inner face of the back member at points between said tongues.

14. In a book including permanently bound signature sections, side covers for the signature sections, means permanently connecting the side covers to the signature sections, hinge sections permanently carried by the side covers, a removable back member for the book, hinge sections fixed to the side edges of the back member, and means detachably connecting the respective hinge sections for securing the back member to said permanently attached side covers.

In testimony whereof we affix our signatures

ERNEST C. HAZEL.
